CLAIM

The ornamental design for a cookware handle as is shown and described herein.

DESCRIPTION

FIG. 1 is a perspective view thereof;
FIG. 2 is a right side elevational view thereof;
FIG. 3 is a left side elevational view thereof;
FIG. 4 is a rear elevational view thereof;
FIG. 5 is a front elevational view thereof;
FIG. 6 is a top plan view thereof; and
FIG. 7 is a bottom plan view thereof.

The broken lines represent parts of the article as well as environmental subject matter. None of the broken lines form part of the claimed design.

1 Claim, 7 Drawing Sheets
